UNITED STATES PATENT OFFICE.

CHARLES F. PYM, OF BEVERLY, MASSACHUSETTS, ASSIGNOR TO UNITED SHOE MACHINERY CORPORATION, OF PATERSON, NEW JERSEY, A CORPORATION OF NEW JERSEY.

PULLING-OVER MACHINE.

Original application filed February 15, 1923, Serial No. 619,120. Divided and this application filed April 28, 1927. Serial No. 187,394.

This invention relates to machines for use in the manufacture of boots and shoes for pulling uppers over lasts, this application being a division of a copending application 5 Serial No. 619,120, filed on February 15, 1923.

Pulling-over machines as commonly constructed comprise grippers for pulling the upper at the opposite sides of the forepart 10 and a gripper for pulling it at the toe end of the last, and in the operation of such a machine the upper is pulled by the several grippers substantially simultaneously and is then held under tension to permit the 15 operator to inspect the work and to make any adjustments which may be necessary before the margin of the upper is laid inwardly over a sole or insole on the bottom of the last and is fastened in overlaid position. The present invention, in one of its 20 important aspects, provides novel gripper-operating means, which in the illustrated embodiment of the invention comprises a novel construction and arrangement of power-operated means for imparting at the will 25 of the operator supplemental movement to one or more of the grippers, after the upper has been pulled, to increase or to lessen the force of the pull applied in one or more locations. The machine illustrated is provided 30 with means for controlling in this manner either of the opposite side grippers or the toe gripper independently, the construction shown comprising a novel arrangement 35 of rack and pinion mechanism associated with each of the grippers for imparting to it supplemental movement either in the direction to increase the force of the pull or in the opposite direction.

40 As a further novel feature, the invention provides power-operated means for enabling the operator to control at will the gripping of the upper by a pair of gripper jaws, as herein illustrated by the toe gripper 45 jaws. In pulling-over machines it is frequently necessary, after the upper has been pulled by the grippers, to adjust the position of the toe gripper jaws relatively to the margin of the upper, for example to cause 50 them to grip the upper either farther from

the plane of the shoe bottom or nearer said plane in order that they may co-operate in the best manner with the means which subsequently lays the margin of the upper inwardly over the insole; and heretofore the 55 operator has been required thus to adjust the gripper manually by partially or wholly opening the gripper jaws and then closing them again on the upper in the desired position. The present invention provides power-operated means by the use of which the operator is enabled to control the opening and closing of the toe gripper jaws after the gripper has pulled the upper, and thus to adjust the position of the jaws 60 with greater facility than heretofore. Advantageously this feature, in the machine herein shown, is combined with power-operated means such as above referred to for imparting to the toe gripper, after the pull, 65 movement either toward the plane of the shoe bottom or away from said plane, so that by use of power-operated means the operator may cause the toe gripper to open and grip the upper in any desired relation to the 70 plane of the shoe bottom and then cause it to pull the upper again with any desired 75 degree of force.

In accordance with a further feature, the invention provides novel means for pulling 80 an upper at the toe of the last. In the construction herein shown the toe gripper comprises a pair of jaws for gripping the upper at the end of the toe and other pairs of jaws for gripping it at the corners of the toe, 85 and for purposes of this invention the corner-gripping jaws are so controlled as to pull the upper inwardly toward the sides of the toe in the upper-pulling operation. This assists in conforming the upper smoothly 90 and tightly to the contour of the last about the toe preparatory to the laying of its margin over the insole.

Included also in the toe gripper herein 95 illustrated is novel means for securing a predetermined relation between the forces with which different pairs of gripper jaws grip the upper. In the construction shown there is provided mechanism for equalizing the forces with which the upper is gripped 100

- by the different pairs of corner gripper jaws, and also means for causing the gripper jaws at the end of the toe to grip the upper with a predetermined greater degree of force than the corner jaws, so as to insure that the portion of the upper at the end of the toe, which it is desired to pull with the greater strain, will be held securely without any tendency to slip in the gripper jaws.
- 10 The above and other features of the invention, including various novel details of construction and combinations of parts, will now be more particularly described by reference to the accompanying drawings and 15 pointed out in the claims.

In the drawings,

Since the general organization of the machine in which the invention is herein shown as embodied is fully illustrated and described in the copending application of which this application is a division, and in the prior Letters Patent referred to in the 65 copending application, only such portions of

the machine as are intimately related to the features of the present invention will be described herein in detail.

For pulling the upper over the last the machine is provided with side grippers, comprising at each side of the forepart two pairs of gripper jaws 2, as common heretofore, and with a toe gripper the construction of which for purposes of the present invention will be hereinafter more particularly set forth. The opposite side grippers are connected respectively to different updraw levers 4, one of which is shown in Fig. 1, the rear ends of these levers being swivelled in blocks 6 which are slidably mounted on updraw rods 8 fast on a vertically movable operating slide 10. Encircling the rods 8 and bearing downwardly upon the blocks 6 through tension adjusting wedges 12 are updraw springs 14 through which movement is imparted yieldingly to the updraw levers upon a downward movement of the slide 10, the slide being operated by the usual cam 16 on a cam shaft 18. The toe gripper is similarly connected to an updraw lever 20 to which movement is imparted yieldingly through an updraw spring 22 from a slide 24 operated by a cam 26 on the shaft 18. Movement is imparted to the shaft 18 intermittently in the course of the cycle of operations from a power shaft (not herein shown), under control of mechanism of the character illustrated in Letters Patent No. 791,986 granted on June 6, 1905 upon an application of R. F. McFeely, this mechanism including a treadle-operated rod 28 which is moved upwardly to start the machine at each stage of the cycle. The work is presented to the machine is illustrated in Fig. 1, with the bottom of the insole in engagement with a sole rest 30, and it will be understood that in the first stage of the cycle the grippers are operated through the mechanism above described to grip and to pull the upper, the sole rest 30 having imparted to it a short downward tipping movement by the action of a cam 32, and at the end of this stage of the cycle the machine comes automatically to a stop with the upper held under tension for the inspection of the operator and for such supplemental operations as may be necessary or desirable, for example to vary the force of the pull of one or more of the grippers or to adjust the tip line in relation to the lines of the last. In this first stage of the cycle also a heel rest 34 is moved forwardly into supporting engagement with the rear end of the shoe, this heel rest being preferably constructed as shown in my copending application above mentioned.

For purposes of this invention, the toe gripper is constructed as shown in Figs. 9 to 14, inclusive. Similarly to grippers heretofore in use in machines of the general type

illustrated, this gripper includes in its organization a gripper bar 36 connected to the updraw lever 20 and a gripper casing 38 provided with lugs 40 for engagement with a portion of the frame of the machine to limit downward movement of the casing; together with a spring 42 which is under compression between an enlarged head 44 on the gripper bar and a member 46 secured within the gripper casing and acts at the beginning of the upward movement of the bar 36 to hold the casing down and thereby to cause the gripper jaws to be closed upon the upper before they begin their upper pulling movement. In a machine having means for lasting the toe, as shown for example in my co-pending application, it is desirable that the upper be gripped and pulled not only at the extreme end of the toe but for a considerable distance round the toe at opposite sides of its middle portion, and for this purpose the gripper herein shown is provided with three pairs of gripper jaws, one pair for engaging the upper at the end of the toe and the other two pairs for engaging it at what may be termed the corners or the sides of the toe. The middle or end pair of gripper jaws comprises a jaw 48 which is fast on the casing 38 and a jaw 50 pivoted at 52 on the casing and provided with an inwardly curved shank portion 54 which is engaged by a pin 56 carried by a jaw-closing slide 58. Each pair of corner gripper jaws comprises a jaw 60 (Fig. 12) fast on a holder 62 and a cooperating jaw 64 pivoted at 66 on said holder. Movable mounted in each of the corner jaw holders 62 is a closing slide 68 provided with pins 70 and 72 for engagement with opposite sides of the inwardly curved shank portion 74 of the jaw 64 to effect respectively closing and opening movements of said jaw. Each corner jaw holder 62 is provided with a substantially cylindrical portion 76 extending upwardly into a socket formed in the casing 38 and mounted to turn in the socket about an axis substantially parallel to the direction of the pull of the gripper. A pin 78 engaging the cylindrical extension 76 in an annular groove 80 (Fig. 12) serves to maintain the holder 62 in place while permitting it to turn as above described.

The turning of the corner jaw holders 62 in the gripper casing is under control of rack bars 82 which are slidably mounted in the casing 38 and engage teeth 84 formed on the extensions 76 of the holders, each rack bar having mounted within it a spring 86 to move it forwardly as far as permitted by a pin 88. Initially, therefore, the corner jaws are inclined outwardly from the middle jaws as shown in full lines in Fig. 15, to facilitate inserting the margin of the upper materials in the three pairs of jaws when the work is presented to the machine. In the upper

pulling movement of the gripper the outer ends of the rack bars 82 are engaged by cam blocks 90 (Fig. 1) which are fast on the frame of the machine and act to force the rack bars inwardly and thus to swing the corner jaws inwardly toward the sides of the toe (see the broken lines of Fig. 15), the toe gripper as a whole being guided in its upward movement by rolls 92 (Fig. 1) which engage the casing 38 in slots 94, so that the gripper pulls in a direction substantially perpendicular to the plane of the insole. Such inward swinging movement of the corner jaws serves to draw the upper close to the last about the toe in preparation, for example, for the subsequent lasting of the toe. In order to pull the upper smoothly and free from wrinkles about the entire toe the three pairs of gripper jaws are arranged to effect a substantially continuous engagement with the upper, the corner jaws, in closed position, extending along the edge of the upper from points approximately contiguous to the middle jaws, as illustrated in Fig. 15. The axes of turning movement of the corner jaw holders, moreover, are substantially coincident with the opposite ends of the fixed middle jaw 48, so that in the inward swinging movement of the corner jaws they are maintained in the same close relation to the middle jaws.

For closing the corner jaws on the upper materials the closing slides 68 have upward extensions provided with annular gear teeth 96 engaged by pinions 98, the different pinions being mounted respectively on different slides 100; and both pinions, moreover, engage annular teeth 102 formed on an upward extension of the closing slide 58 for the middle pair of jaws. As shown in Fig. 9, the upper ends of the slides 100 are recessed and provided with rack teeth engaging respectively the opposite sides of a pinion 104, this pinion being mounted on a holder 106 arranged to be connected by a spring-controlled latch 108 to the gripper bar 36, the latch being pivoted on the lower end of the bar. It will be evident that, as the parts are thus constructed and arranged, upward movement of the gripper bar 36 results in moving the holder 106 with its pinion 104 upwardly in the casing 38, the pinion acting to raise the slides 100 with their pinions 98 and thereby to impart jaw-closing movement both to the closing slides 68 of the corner jaws and to the closing slide 58 of the middle jaws. It will also be evident that in response to any differences which there may be in the thickness of the upper materials at the opposite corners of the toe the slides 100 are permitted to move relatively by reason of the equalizing connection afforded by the pinion 104, and that as a result the gripping pressures of the different pairs of corner jaws are substantially equalized. It

will likewise be understood that each pinion 98 serves in the manner of an equalizing connection between its corner jaw closing slide 68 and the middle jaw closing slide 58, but 5 since the middle slide is connected to both these pinions the closing force applied to the middle jaw 50 is twice that applied to either of the pivoted corner jaws 64. The provision of means for applying thus a positively determined greater degree of gripping 10 pressure to the upper at the end of the toe than to portions of the upper engaged at the corners of the toe serves to insure that the portion of the upper which it is desired to 15 subject to the greatest strain will be held securely without any tendency to slip in the gripper jaws.

After the machine has come to a stop with the upper held under tension, the operator 20 may move the opposite side grippers relatively lengthwise of the last to adjust the angular relation of the tip line to the longitudinal median line of the last by manipulation of a lever (not shown), as in prior 25 machines. The conditions observed at this stage sometimes also render it desirable to move one or more of the grippers in a direction to increase or to lessen the force of the pull. For example, it may be desired 30 to apply a harder pull through the side grippers to draw the upper closely to the last at the back of the toe, or by relaxing the force of the pull at one side and increasing it at the other side to adjust the upper 35 by slipping it transversely of the last. At the toe, moreover, it may be desired to increase or to lessen the force of the pull, for example in order to straighten the tip line, or conditions may render it necessary to adjust 40 the toe gripper on the upper, for example to position the gripper jaws at a higher elevation in preparation for subsequent operations. For these and other purposes, the machine is provided with power means 45 for imparting supplemental movements to the different grippers selectively, as shown particularly in Fig. 2 of the drawings and more in detail in other figures comprising Figs. 3 to 8, inclusive. It will be noted that 50 the right-hand side gripper lever 4 is connected at its rear end (Fig. 2) by a link 112 to an arm 114 which is fast on a rock shaft 116 mounted to turn in bearings in a bracket 118 on the rear 55 of the machine, the shaft 116 having fast thereon on arm 120 connected by a link 122 to a block 124 fast on the upper end of a rod 126 which is mounted to slide vertically in a support 128 mounted on the righthand 60 side of the machine. Fast on the lower end of the rod 126 (Fig. 4) is a block 130 on which is pivoted at 132 a double or forked rack member 134 having opposite sets of rack teeth 136 and 138 arranged for engagement alternatively with the teeth of a

pinion 140 fast on a shaft 142. Movement in the direction of the arrow may be imparted to this shaft by any convenient or suitable means, such as an electric motor (not shown) connected by a belt 146 (Fig. 2) to a pulley 148 which is fast on a shaft 150 mounted to turn in bearings formed in a bracket mounted on the side of the machine. The shaft 150 carries an eccentric 152 which operates a pitman 154 connected to a lever 156 mounted to oscillate on a fixed pivot 158, the lever 156 being connected by a link 160 to an arm 162 which is fast on a sleeve 164 (Fig. 8) serving as one of the members of a Horton clutch mounted on the shaft 142. Inside of the sleeve 164 is a co-operating clutch member 166 with a series of rolls 168 which act in a well-known manner to transmit movements of the sleeve 164 in the direction of the arrow to the shaft 142. It will be understood that the arm 162 is rapidly oscillated at all times through its connections to the motor, and that as a result intermittent turning movements all 80 in the same direction are imparted to the pinion 140, reverse movement of the shaft 142 and its pinion being prevented by the action of a second Horton clutch 170 mounted adjacent to the driving clutch, as 85 shown in Fig. 5, and provided with an arm 172 (Fig. 8) which is fast to the frame. While it has been found convenient in the organization herein shown thus to impart intermittent turning movements to the pinion 140, it is to be understood that the invention is not dependent upon or restricted to movement of that particular character. 90

By reference to Fig. 4 it will be seen that if the front series of teeth 136 on the member 134 are moved into engagement with the pinion 140, the pinion will act on these teeth through the connections above described to impart downward movement to the rear end of the right-hand gripper lever 4 to move the gripper in the direction to increase the force of its pull on the upper, and that if the rear series of teeth 138 are engaged with the pinion the opposite result will be effected and movement imparted to the gripper in the direction to relax the force of the pull. For accomplishing either of these results at will the rack member 134 is under control of a handle 174 (Fig. 2) through connections including a rocker 176 mounted to turn about the axis of the shaft 142 and having projections 178 which bear respectively on the shaft and on a bushing encircling the pinion 140 (Fig. 5), and which embrace and guide between them the lower end of the rack member 134. An upward and rearward extension of the rocker 176 is provided with a roll 180 positioned in a vertical slot 182 in the rack member 134, and a forward extension of the rocker is engaged on its upper and lower faces by spring 130

plungers 184 whereby the rocker is maintained normally in a central or neutral position with both series of rack teeth 136 and 138 out of engagement with the pinion 140. The handle 174 is connected to the rocker 176 by means of a block 186 which is pivoted at 188 on the forward extension of the rocker. To understand the action of the handle 174 on the rocker 176 it is necessary to refer at this point to means provided for locking the rod 126 against return upward movement from any position to which it is moved in subjecting the upper to tension. For this purpose the rod is provided with a series of ratchet teeth 190 engaged by a complementally toothed retaining member or catch 192 pressed by springs 194 inwardly against the teeth 190. Extending outwardly from the member 192 is a rod 196 having on its outer end a head portion with a cross pin 198 engaged by one arm of a bell-crank lever 200. The other arm of the bell-crank 200 is connected by a link 202 to one arm of a bell-crank 204, and the other arm of the latter is connected by a link 206 to the block 186 which carries the handle 174. It will be seen that as the parts are positioned in Fig. 4, which is their normal or idle position, the member 192 is in engagement with the teeth on the rod 126, and consequently if an upward pull is applied to the handle 174 the block 186 is restrained by its connections to the bell-crank 200 and by engagement of the latter with the member 128 from turning about its pivot 188, so that by upward movement of the handle the forwardly extending arm of the rocker 176 is lifted against the resistance of the upper spring plunger 184 and the roll 180 acts to impart rearward swinging movement to the rack member 134 to carry the teeth 136 into engagement with the pinion 140. The pinion then acts to impart downward movement to the rack member and to the rod 126 and thereby to move the right-hand side gripper positively in the direction to increase the force of its pull on the upper, the length of such supplemental movement depending upon how long the operator continues the upward pull on the handle. It will also be evident that the locking member 192 acts automatically to lock the gripper against return movement and to hold it locked after the operator permits the rocker 176 to return to its initial position. If it should be desired for any reason to move the ripper in the direction to lessen the force of the pull, either before or after it has received such supplemental pulling movement, the operator bears downwardly on the handle 174. In view of the fact that the springs 194 are weaker than the spring that controls the lower plunger 184, the first effect of such downward pressure on the handle is to turn the member 186 about its pivot 188 and thereby through the

connections above described to withdraw the catch 192 from engagement with the teeth 190. Further downward pressure on the handle then serves to swing the rocker 176 in the direction to bring the teeth 138 into engagement with the pinion 140, whereupon the pinion acts to impart upward movement to the rod 126 and thereby to move the gripper positively downward to relax the force of the pull as determined by the length of time the operator holds the handle depressed. When the operator releases the handle the member 192 returns to its locking position, and incidentally it may be observed that since this member is in locking position at the time when the grippers receive their main upper pulling movement as hereinbefore described, resulting of course in downward movement of the rod 126 and of the member 134, it acts to lock its gripper against return movement at that time in the cycle as well as against return from any position to which it may be moved by the supplemental pulling means. In order to prevent danger of breakage in case the operator should maintain the upward pull or downward pressure on the handle 174 too long, the machine is provided with a pin 208 (Fig. 4) which is arranged for engagement with one or the other of a pair of cam faces 210 formed in a recess in the rack member 134 to throw this member out of engagement with the pinion 140 before it is moved too far in either direction.

Mechanism which is substantially a duplicate of that above described is provided for controlling the left-hand side gripper, this mechanism including a handle 212 which is the left-hand one of the series of handles shown in Fig. 2. It is to be noted, however, that the connections to the left-hand gripper lever 4 comprise a yoke member 214 which is mounted to turn on the shaft 116, this yoke member having at one end an arm 216 connected by a link to the gripper lever and at its other end an arm 218 connected to the corresponding link 122.

Mechanism which is substantially a duplicate of that associated with each of the side gripper levers is provided for imparting also to the toe gripper lever 20 movement in a direction to increase the force of the pull or in the opposite direction, this mechanism including a locking device, of the same construction and mode of operation as that shown in Fig. 4, for holding the toe gripper from retractive movement, and including also a rack member 220 (Fig. 6) which is substantially like the rack member 134 (Fig. 4) except for a slight mechanical difference in the shape of the recess provided for preventing excessive movement of the gripper. The supplemental movements of the toe gripper are controlled by a handle 222, and it may also be noted that the connections

70

75

80

85

90

95

100

105

110

115

120

125

130

between the gripper lever 20 and the corresponding rod 126 comprise a rock shaft 224 which is mounted in the bracket 118 and has thereon an arm 226 connected by a link 228 to the rod 126 and an arm 230 connected by a link 232 to the rear end of the toe gripper lever 20.

In addition to the means provided for imparting supplemental upper pulling or tension relaxing movement to the toe gripper, the machine is also provided with mechanism whereby, through power derived from the pinion 140, the toe gripper jaws may be caused to relax their grip on the upper, for example to permit the upper to slip more or less in the jaws if it should be desired to position the jaws farther from the plane of the insole, or it may be to cause the jaws entirely to release the upper. This mechanism is controlled by a fourth handle 234 and in its constructional details is substantially a duplicate of the mechanism illustrated in Fig. 4, including the locking device, except that, as a matter of design, the rack 25 member is shaped as shown at 236 in Fig. 7. The corresponding rod 126 of this mechanism is connected by a link 238 to an arm 240 which is part of a yoke member 242 pivoted on the shaft 224, this yoke member having another arm 244 connected by a link 246 to a lever 248 which is pivoted at 250 on the toe gripper updraw lever 20. At its front end the lever 248 is pivotally connected to a short plate 252 in which is formed a rectangular recess 254 to receive the rearwardly curved end of a finger 256 fastened to the upper end of the toe gripper casing 38. It will be understood from the description before given of the construction of the toe gripper that an upward movement of the gripper casing 38 relatively to the gripper bar 36 will serve to relieve the pull of the latch 108 on the gripper jaw closing devices, thereby permitting the upper to slip in the jaws, or if the casing is lifted far enough, will cause the jaws to open and release the upper. It will be evident that such upward movement will be imparted to the gripper casing by the action of the plate 252 on the finger 256, through the action of the pinion 140, when the rack member 236 is engaged with the pinion by lifting the handle 234, and that the associated locking device will hold the gripper-releasing connections 55 against retractive movement until the operator depresses the handle, which he will do when he desires to restore the gripper-releasing connections to their original position. If desired, by manipulation of both the handles 222 and 234 the operator may cause the toe gripper to open and to move down and grip the upper nearer to the insole and thereafter to pull the upper again as hard as may be desired. The slot 254 in the plate 252 is 65 sufficiently elongated not to interfere with

the normal relative movements of the gripper bar and the gripper casing in closing and opening the gripper jaws.

It will be evident that in the return of the parts of the machine to starting position 70 after the operations on the shoe have been completed the upward movement of the rear ends of the gripper levers in response to the return upward movement of the slides 10 and 24 serves through the connections described 75 to impart upward movement to the rods 126 which are associated with the different levers and thus to restore the supplemental gripper-operating mechanisms to their original positions. In order to permit such return of 80 the parts, the machine is provided with means for automatically withdrawing the locking members 192 from engagement with the teeth 190, this means comprising a yoke shaped member 258 (Figs. 3 and 4) which 85 is pivotally mounted at the rear of the member 128 and carries a rod 260 in position to engage the rearwardly extending arms of the different bell-crank levers 200. The member 258 is operated by a cam 262 (Fig. 90 2) on the cam shaft 18 through engagement of the cam with a roll 264 on a slide 266, the slide having a pin 268 which engages the lower forked end of an arm 270 projecting downwardly from the member 258. It will 95 be observed that the cam 262 moves the slide 266 rearwardly and thereby operates the rod 260 to turn the bell-crank levers 200 and withdraw the locking members 192 from 100 engagement with the different respective 105 rods 126, this operation occurring in proper time relation to the return movement of the gripper levers. Before the cam shaft 18 arrives at the end of its cycle the cam 262 releases the roll 264, permitting the springs 110 194 to return the locking members to operative position ready for the operation of the machine upon the next shoe.

The manner of operation of the novel toe gripper and of the different gripper-controlling mechanisms has been fully set forth in the foregoing description and requires no further explanation.

Having described the invention, what I claim as new and desire to secure by Letters 115 Patent of the United States is:—

1. In a machine of the class described, the combination with an upper-pulling gripper, of power-driven mechanism for moving said gripper at the will of the operator either in 120 a direction to pull the upper or in a direction to relax the force of the pull, said mechanism comprising a power-driven pinion, racks connected to the gripper for moving it respectively in said different directions, and manual means for connecting the pinion to one or the other of said racks alternatively.

2. In a machine of the class described, the combination with an upper-pulling gripper, 125

of power-driven mechanism for moving the gripper either in a direction to pull the upper or in a direction to relax the force of the pull, said mechanism comprising a power-driven pinion, a member connected to the gripper and having different sets of rack teeth formed thereon for engagement respectively with opposite sides of the pinion, and manual means for moving said member to engage one or the other of said sets of teeth with the pinion at the will of the operator.

3. In a machine of the class described, the combination with a gripper and means for effecting relative movement of said gripper and a last to pull an upper, of supplemental operating means for moving the gripper either to increase or to lessen the force of the pull, said supplemental means comprising a power-driven pinion, opposite sets of rack teeth connected to the gripper, and manual means for connecting the pinion to either of said sets of rack teeth alternatively.

4. In a machine of the class described, the combination with a plurality of grippers for gripping an upper in different locations, and means for effecting relative movement of said grippers and the last to pull the upper, of supplemental power-operated means for imparting to one or another of said grippers selectively movement to vary the force of the pull, said supplemental means comprising a power-driven member common to the different grippers, and members connected to the different respective grippers and movable selectively at the will of the operator into or out of operative engagement with said power-driven member.

5. In a machine of the class described, the combination with a plurality of grippers for gripping an upper in different locations, and means for effecting relative movement of said grippers and the last to pull the upper, of supplemental power-operated means for imparting to one or another of said grippers selectively movement to vary the force of the pull, said supplemental means comprising a power-driven pinion, rack members connected respectively to the different grippers and movable into or out of engagement with said pinion, and manual means enabling the operator to move any one of said rack members selectively into engagement with the pinion.

6. In a machine of the class described, the combination with a plurality of grippers for gripping an upper in different locations, of power-driven mechanism for moving one or another of said grippers selectively either in a direction to pull the upper or in a direction to relax the force of the pull, said mechanism comprising a power-driven pinion, members connected to the different respective grippers and provided with different sets of rack teeth for engagement re-

spectively with opposite sides of said pinion, and manual means to enable the operator to move any one of said members to engage either of its opposite sets of rack teeth with said pinion.

7. In a machine of the class described, the combination with a gripper comprising upper-gripping jaws, and means for effecting relative movement of said gripper and a last to pull an upper over the last, of power-operated means for controlling said jaws while the gripper is in upper-pulling position to cause the jaws to relax more or less, as determined by the operator, their gripping pressure on the upper.

8. In a machine of the class described, the combination with toe and side grippers for pulling an upper and for holding it under tension, of power-operated controlling means for the toe gripper arranged for optional use to cause said gripper in its upper-pulling position to relax its grip on the upper and permit the upper to slip in the gripper and thereafter again to grip and hold the upper.

9. In a machine of the class described, the combination with a gripper comprising upper-gripping jaws and a gripper bar and a gripper casing relatively movable to cause said jaws to grip or to release the upper, of manually controlled power-operated means for moving said casing relatively to the gripper bar at the will of the operator to cause the gripper to relax its grip on the upper.

10. In a machine of the class described, the combination with side grippers, and a toe gripper comprising upper-gripping jaws and a gripper bar and a gripper casing relatively movable to cause said jaws to grip or to release the upper, of manually controlled power means connected to said gripper casing for moving said casing relatively to the gripper bar at the will of the operator to cause the toe gripper to relax its grip on the upper while the side grippers maintain their hold on the upper.

11. In a machine of the class described, the combination with side grippers, and a toe gripper comprising upper-gripping jaws and parts relatively movable to cause said jaws to grip or to relax their grip on an upper, of power-operated means for controlling said relatively movable parts while the gripper is in upper-pulling position comprising a member movable in one direction to cause the gripper to relax its grip on the upper and movable at the will of the operator in the reverse direction to cause the gripper again to grip and hold the upper.

12. In a machine of the class described, the combination with a gripper and a gripper lever, and means for operating said lever to cause the gripper to pull an upper, of power-driven means for controlling said

- gripper independently of the gripper lever and arranged for optional use after the upper-pulling operation to cause the gripper to relax its grip on the upper.
13. In a machine of the class described, the combination with a gripper and means for operating it to pull an upper, of power-driven means for controlling said gripper independently of its operating means to cause it to relax its grip on the upper and thereafter again to grip and hold the upper.
14. In a machine of the class described, the combination with a gripper, and means for effecting relative movement of said gripper and a last to pull an upper, of supplemental power means for moving the gripper at the will of the operator either in the direction of the pull or in the reverse direction, and power-driven means arranged for optional use and operative independently of said supplemental power means to cause the gripper to relax its grip on the upper.
15. In a machine of the class described, the combination with a gripper, of power-driven means for moving said gripper at the will of the operator either in a direction to pull the upper or in a direction to relax the force of the pull, and power-operated means arranged for optional use to cause the gripper to release and to re-engage the upper.
16. In a machine of the class described, the combination with a gripper, of power-driven mechanism for moving said gripper at the will of the operator either in a direction to pull the upper or in the opposite direction, power-operated mechanism for controlling the gripper to open its jaws or to close them on the upper, and manually operated members for controlling respectively said different power mechanisms.
17. In a machine of the class described, means for gripping an upper about the toe of a last and for pulling the upper heightwise of the toe, comprising upper-gripping members automatically controlled to pull the upper inwardly toward the sides of the toe by movement transverse to the longitudinal axis of the shoe as the upper is pulled heightwise of the toe.
18. In a machine of the class described, a toe gripper comprising opposite pairs of gripper jaws mounted to move toward each other laterally of the toe to pull the upper inwardly at the sides of the toe, means for effecting relative upper-pulling movement of said gripper and a last heightwise of the toe, and mechanism automatically operative in said relative movement of the gripper and the last to move said pairs of jaws toward each other.
19. In a machine of the class described, a toe gripper movable heightwise of the toe to pull an upper and comprising different pairs of gripper jaws mounted to swing laterally of the toe to pull the upper inwardly at the

sides of the toe, and mechanism automatically operative in the movement of said gripper heightwise of the toe to impart inward pulling movements to said jaws.

20. In a machine of the class described, a toe gripper comprising different pairs of gripper jaws mounted for swinging movements about axes substantially perpendicular to the plane of the shoe bottom to pull the upper inwardly at the sides of the toe, means for effecting relative movement of said gripper and a last heightwise of the toe to pull the upper, and mechanism automatically operative in said relative movement of the gripper and the last to impart inward swinging movements to said jaws.

21. In a machine of the class described, a toe gripper comprising different pairs of gripper jaws mounted to swing laterally of the toe about axes substantially perpendicular to the plane of the shoe bottom, said gripper having thereon connections for imparting the swinging movements to the jaws, means for moving said gripper heightwise of the toe to pull the upper, and relatively stationary means arranged to operate said connections in such heightwise movement of the gripper to impart inward swinging movements to said jaws to pull the upper toward the sides of the toe.

22. In a machine of the class described, a toe gripper comprising different pairs of gripper jaws mounted for swinging movements laterally of the toe about axes substantially perpendicular to the plane of the shoe bottom, said gripper having rack bars thereon connected respectively to said different pairs of jaws to swing them inwardly, and means for operating said rack bars in response to the upper-pulling movement of the gripper to impart inward swinging movements to said jaws.

23. In a machine of the class described, a toe gripper comprising a pair of gripper jaws for gripping an upper at the end of the toe and opposite pairs of gripper jaws for gripping the upper at the corners of the toe, said corner gripper jaws being mounted to swing laterally of the toe about axes substantially perpendicular to the plane of the shoe bottom and substantially adjacent to the opposite ends of the end gripper jaws for pulling the upper inwardly about the toe.

24. In a machine of the class described, a toe gripper comprising a pair of gripper jaws for gripping an upper at the end of the toe and opposite pairs of gripper jaws for gripping the upper at the corners of the toe, said corner gripper jaws being mounted to swing laterally of the toe about axes substantially perpendicular to the plane of the shoe bottom and substantially adjacent to the opposite ends of the end gripper jaws, and means for imparting inward swinging

movements to said corner gripper jaws in the upper-pulling operation of the gripper.

25. In a machine of the class described, a toe gripper comprising a pair of end gripper jaws and opposite pairs of corner gripper jaws mounted to swing relatively to said end jaws laterally of the toe, spring means for swinging said corner jaws outwardly, and mechanism automatically operative in the upper-pulling operation to swing said corner jaws inwardly.

26. In a machine of the class described, a toe gripper comprising a pair of end gripper jaws and opposite pairs of corner gripper jaws, holders for said corner gripper jaws mounted to turn about axes substantially perpendicular to the plane of the shoe bottom, said holders having rack teeth thereon, and rack bars engaging said teeth for controlling turning movements of said holders.

27. In a machine of the class described, a toe gripper having a pair of end gripper jaws and opposite pairs of corner gripper jaws, holders for said corner gripper jaws mounted to turn about axes substantially perpendicular to the plane of the shoe bottom, said holders having rack teeth thereon, rack bars for engaging said teeth to control the turning movements of the holders, spring means for forcing said rack bars outwardly, and means for engaging said rack bars in the upper-pulling movement of the gripper to swing the corner jaws inwardly.

28. In a machine of the class described, a toe gripper comprising different pairs of gripper jaws, and jaw-closing gear mechanism automatically operative to apply greater gripping pressure to the upper through one pair of jaws than through another pair.

29. In a machine of the class described, a toe gripper having different pairs of gripper jaws for gripping an upper respectively at the end of the toe and at opposite sides of the toe, and positively operating controlling means for said gripper jaws automatically operative to cause the end gripper jaws to grip the upper with a positively determined greater degree of pressure than the side gripper jaws.

30. In a machine of the class described, a toe gripper having different pairs of gripper jaws for gripping an upper respectively at the end of the toe and at the sides of the toe, a member movable to close said jaws on the upper, and positive connections between said member and the different pairs of jaws constructed to apply greater closing force to the end jaws than to the side jaws.

31. In a machine of the class described, a toe gripper comprising different pairs of gripper jaws for gripping an upper respectively at the end of the toe and at opposite sides of the toe, and means for closing said jaws on the upper comprising closing con-

nnections positively determining the relative pressures of the different pairs of jaws on the upper and constructed to apply automatically through the end pair of jaws upper-gripping pressure substantially equal to the sum of the pressures applied through the jaws that grip the upper at the sides of the toe.

32. In a machine of the class described, a toe gripper comprising different pairs of gripper jaws for gripping an upper respectively at the end of the toe and at the opposite sides of the toe, a member movable to close said jaws, and connections between said member and the different pairs of jaws comprising relatively movable racks and connecting pinions for applying to the end jaws and the side jaws closing forces in predetermined relation to each other.

33. In a machine of the class described, a toe gripper comprising different pairs of jaws for gripping the upper respectively at the opposite sides of the toe, and jaw-closing means comprising relatively movable rack bars connected respectively to said different pairs of jaws and a pinion engaging said rack bars for substantially equalizing the closing forces applied to the different pairs of jaws.

34. In a machine of the class described, a toe gripper comprising a pair of end jaws and opposite pairs of side jaws, and means for closing said jaws comprising an equalizing connection between each pair of side jaws and the end jaws.

35. In a machine of the class described, a toe gripper comprising a pair of end jaws and opposite pairs of side jaws, and means for closing said jaws comprising an equalizer between each pair of side jaws and the end jaws, relatively movable supports for said equalizers, and an equalizer between said relatively movable supports.

36. In a machine of the class described, a toe gripper comprising a pair of end jaws and opposite pairs of side jaws, closing slides for said different pairs of jaws having rack teeth thereon, pinions connecting the closing slides for the side jaws to the closing slide for the end jaws, and means for moving said pinions bodily to close said different pairs of jaws.

37. In a machine of the class described, a toe gripper having a pair of end jaws and opposite pairs of side jaws, closing slides for the different respective pairs of jaws, an equalizer between the closing slide for each pair of side jaws and the closing slide for the end jaws, relatively movable supports for said equalizers, and means for operating said relatively movable supports to close the jaws.

38. In a machine of the class described, a toe gripper having a pair of end jaws and opposite pairs of side jaws, closing slides

for the different respective pairs of jaws having rack teeth thereon, pinions connecting the closing slides for the side jaws to the closing slide for the end jaws, relatively movable supports for said pinions, said supports having rack teeth thereon, and means for imparting jaw-closing movement to said supports comprising a pinion engaging said last-mentioned rack teeth to permit the supports to move relatively to each other in the closing of the jaws.

39. In a machine of the class described, a toe gripper comprising a pair of end jaws and opposite pairs of side jaws, each pair of

side jaws being mounted to turn about an axis substantially perpendicular to the plane of the shoe bottom, and jaw-closing means comprising members for connecting the end pair of jaws to the side pairs of jaws in any position assumed by the side jaws in turning about said axes, said members being movable to control automatically the relative closing pressures of the end jaws and the side jaws.

In testimony whereof I have signed my name to this specification.

CHARLES F. PYM.
